UNITED STATES PATENT OFFICE.

JOSEPH W. MOORE, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

APPARATUS FOR MANUFACTURING SEGMENTS OF TURBINE-BLADES.

1,187,447.

Specification of Letters Patent. Patented June 13, 1916.

Application filed August 11, 1913, Serial No. 784,633. Renewed November 6, 1915. Serial No. 60,415.

To all whom it may concern:

Be it known that I, JOSEPH W. MOORE, a citizen of the United States, residing at West Allis, Milwaukee, in the county of Milwaukee and State of Wisconsin, have invented a certain new and useful Improvement in Apparatus for Manufacturing Segments of Turbine-Blades, of which the following is a specification.

10 This invention relates to apparatus for manufacturing segments of turbine blades. This invention primarily concerns segments of turbine blades in which a base is cast around the ends of the blades. Heretofore it has been difficult to satisfactorily cast said base with the blades in correct position. Moreover it has been difficult to secure a perfect surface of the cast metal between the blades, as this surface is unmachinable because of inaccessibility after casting.

15 The object of this invention is to provide apparatus which will insure accuracy of spacing and angling of the blades as well as correct radial position, and accuracy of the unmachinable wall of the space between blades and generally facility of production of correct segments.

20 The process, in the carrying out of which the present apparatus may be utilized, is claimed broadly in a divisional application 25 Serial No. 821,316, filed Feb. 24, 1914.

Referring to the drawings.—Figure 1 shows a plan view of a frame having clamped thereto a plurality of blades having a shroud strip connected thereto. Fig. 2 is a sectional view of the showing in Fig. 1 on the line II—II thereof. Fig. 3 is a developed end view of the same. Fig. 4 is a side view of the same showing in addition strips temporarily clamped on opposite sides of the plurality of blades. Fig. 5 is a plan view of the showing of Fig. 4, additionally showing a tamping tool in operative relation. Fig. 6 is an end view of the tamping tool. Fig. 7 is a transverse sectional detail view of the segment with the blades lying in position within the mold shown in section. Fig. 8 is a transverse sectional detail view of the segment with the blades called into position in the turbine spindle or casing.

50 Referring to the drawings, a segment shaped frame 1 having an arc-shaped stop portion 2 at one end, has connected thereto permanently or otherwise, a notched strip 3,

also arc-shaped and in parallel relation with the stop portion 2. Side blocks 4, 5, are positioned at the respective sides of the frame 1 and with reference to the notches of strip 3, see Fig. 3, so as to insure correct angling and radial positioning of the blades 15, and are of thickness substantially equal to the width of the segment of blades. An arc-shaped clamping strip 6 extends from block 4 to block 5 across the segment of blades, and lies parallel to the stop portion 2. Stud bolts 7, 7, extend through the clamping strip 6 and side blocks 4, 5, into the frame 1 and serve to hold the segment of blades in place on the frame. Other stud bolts 8, 8, pass through blocks 4, 5, and into frame 1, serving to additionally secure these blocks in place. A strip of asbestos paper 9 may extend underneath clamping strip 6 and between it and the blocks 4, 5, and segment of blades, see Figs. 2, 3 and 4.

75 Strips 11, 12, may be temporarily clamped at opposite sides of the segment of blades by means of clamps 13, 14.

In using the apparatus of this invention a plurality of blades 15 are connected to a shroud strip 10 by forming integral tenons of irregular section at the ends of the blades and passing same into correspondingly shaped holes punched into the shroud strip. This will insure proper angle of blades in the strip. A temporary fastening connection of any kind may be used. The segment of blades thus temporarily assembled is placed in position on the frame 1 with the shroud strip against the stop portion 2 and the blades in their respective notches of strip 3. The end blade is brought into correct angular and radial position with its concave working face in coaction with the adjacent surface of the block 5 by simultaneously swinging, if necessary, the blades in their retaining notches as centers, thus skewing the entire segment into correct position. After being sure that the shroud strip 10 is against the stop portion 2 at all points and the end blade against its side block 5, the clamping strip 6 with its underlying asbestos paper 9 is brought down upon the segment of blades and clamped to the frame and against the side blocks 4, 5. The paper 100 prevents injury to the blade edges. With the blades 15 thus clamped, the end blade 15 adjacent the block 5 has its concave work-

ing face in contact with the adjacent convex surface of the block 5, and the end of the blade 15 adjacent the block 4 has its convex working face in contact with the adjacent concave surface of the block 4, see Figs. 1 and 3.

After ramming sand between the blades, strips 11, 12, are temporarily clamped on opposite sides respectively of the segment of blades with their edges adjacent the ends of the blades in line and in a position a short distance nearer the adjacent ends of the blades than would correspond to the limit of entry of cast metal between the blades, see Fig. 4, and the sand is then brushed out or otherwise removed from between the ends of the blades up to the edges of the strips 11, 12. These strips 11, 12, are then moved away from the ends of the blades the same short distance referred to, see Fig. 5, and a tamping tool 16, having a cross section substantially equal to the cross section of the space between two blades, is rammed between each two of the blades until a shoulder 17 formed thereon is brought into contact with the ends of the blades. This will gage and positively determine the limit of entry of the cast metal between the blades during the casting operation. The strips 11, 12, are now removed.

A mold of sand having previously been prepared by embedding a pattern therein of the proper shape to accommodate the substitution of the frame as prepared with its segment of blades and also to additionally form a cored space 18 in the mold adapted to receive the cast metal about the ends of the blades of the segment, the frame with the segment of blades is placed therein with the free ends of the blades projecting into the cored space 18, see Fig. 7. The mold after insertion of the frame and blade segment, is then properly closed by the cope, proper and necessary sprue and riser openings having been formed leading to and from the cored space 18 for the cast metal. The ends of the blades, it should be stated, may be notched or roughened or formed in any way to make a positive lock with the cast metal, see Figs. 2, 4, 7 and 8. The metal is then cast about the ends of the blade and as soon as the metal has set the frame is removed from the mold and the clamping strip 6 is loosened from the frame or entirely removed, to permit of the shrinkage which takes place during cooling. The segment is then machined by turning down the cast metal to proper shape for calking in the spindle or cylinder of the turbine. The fastening to the spindle is preferably made by undercutting the parts rather than by dovetailing, as this affords a positive locking of the parts.

It should be understood that it is not desired to be limited to the exact detail of construction of apparatus shown and described

or details of process, disclosed, for obvious modifications will occur to a person skilled in the art.

It is claimed and desired to secure by Letters Patent,

1. A frame having an arc-shaped stop portion, a notched strip extending across said frame, a stop block at one side of said frame, located with reference to the first notch of the notched strip so as to determine the correct radial position of the adjacent blade of a segment of turbine blades having a spacing and angle determining means connected therewith, and means for clamping said segment against said arc-shaped portion of said frame with said blades lying in the notches of said strip and with said block in contact with said adjacent blade. 70 75

2. A frame for clamping thereto a segment of turbine blades, strips clamped on opposite sides of said segment, and a gaged tamping tool for ramming back molding sand between blades a definite distance from the end thereof. 80 85

3. A frame having an arc-shaped stop portion, a notched strip extending across said frame, a stop block at one side of said frame, located with reference to the first notch of the notched strip so as to determine the correct radial position of the adjacent blade of a segment of turbine blades having a spacing means connected therewith, and means for clamping said segment against said arc-shaped portion of said frame with said blades lying in the notches of said strip and with said block in contact with said adjacent blade. 90 95 100

4. A frame having an arc-shaped stop portion, a notched strip extending across said frame, a stop block at one side of said frame, located with reference to the first notch of the notched strip so as to determine the correct radial position of the adjacent blade of a segment of turbine blades having an angle-determining means connected therewith, and means for clamping the segments against said arc-shaped portion of said frame with said blades lying in the notches of said strip and with said block in contact with the adjacent blade. 105 110 115

5. A frame having an arc-shaped stop portion, means for clamping segments of turbine blades against said frame with the corresponding ends of the blades abutting said arc-shaped portion, and means for ramming back molding sand between the opposite ends of the blades a definite distance from said ends. 120

6. In an apparatus for clamping segments of turbine blades having spacing and angle-determining means connected therewith, a frame having a stop portion, a blade spacing strip extending across said frame, a stop block located with reference to said blade-spacing means so as to determine the correct 125 130

radial position of one of the blades of a segment, said strip coacting with the remaining blades of the segment so as to determine the correct radial positions thereof, and 5 means for clamping said blades against said frame.

7. In an apparatus for manufacturing segments of turbine blades, means for spacing and for determining the angles of a 10 plurality of blades forming a segment, a frame having an arc-shaped stop portion for aligning adjacent ends of the blades, means on said frame coacting with said spacing means and with said stop portion for determining the correct radial positions of the 15 blades, and means for clamping the blades against said frame.

8. In an apparatus for manufacturing segments of turbine blades, means for spacing and for determining the angles of a plurality of blades forming a segment, a frame, 20 means for clamping said blades to said frame, means for permitting filling of the spaces between the free ends of the blades with molding sand, and means for ramming back molding sand from between said free ends a definite distance.

In testimony whereof, I affix my signature hereto in the presence of two witnesses.

JOSEPH W. MOORE.
